UNITED STATES PATENT OFFICE.

CHARLES R. OLBERG, OF VIENNA, VIRGINIA, ASSIGNOR OF ONE-HALF TO FRANCIS R. WELLER, OF WASHINGTON, DISTRICT OF COLUMBIA.

WRENCH.

No. 901,821.

Specification of Letters Patent. Patented Oct. 20, 1908.

Application filed July 25, 1907. Serial No. 385,484.

To all whom it may concern:

Be it known that I, CHARLES R. OLBERG, a citizen of the United States, residing at Vienna, in the county of Fairfax and State of Virginia, have invented certain new and useful Improvements in Wrenches, of which the following is a specification, reference being had therein to the accompanying drawing.

The improvements provided by this invention in general pertain to tools which are used to turn into or out of place nuts, bolt-heads, taps, or the like, or to hold such a part in fixed position while another part with which it is connected is being turned; and, while they particularly relate to nut-wrenches, they are also susceptible of embodiment in pipe or other wrenches.

The invention contemplates a wrench the parts of which are so formed and combined that the jaws, when engaged with a nut or other part to be turned, will automatically clutch the same as force is applied to the clutching mechanism, and the greater the force applied in imparting a rotative movement, the greater will be the clutching force of the jaws. When force is applied in a direction contrary to the original, the jaws will be automatically released.

The operative parts of the wrench are constructed and arranged in such manner that the jaws will automatically clutch the object with which they are engaged when the clutching mechanism is moved in either direction of rotation, the wrench being thereby adapted to turn either a right or left handed screw-threaded object on or off the part to which such object is applied.

The means which operate to cause the jaws to clutch or release are so constructed that they may be easily removed for substitution by jaws of the same or of another character, when desired. Means are also provided by this invention whereby the jaws may be maintained, when desired, in any fixed position.

Associated with the jaw-actuating means is a ratchet mechanism of novel construction, whereby a reciprocatory movement of the wrench-handle will result in successive rotations in the object being turned, the ratchet mechanism being arranged for as effective operation when direction of rotation is in one direction as when it is in the other.

Other novel characteristics of the invention reside in the means for maintaining the

jaw-actuating instrumentalities in efficient operative position, and in the peculiar formation and arrangement of the various parts of the device.

When read in connection with the following description, the details of construction and arrangement of parts contemplated by this invention will be apparent from the accompanying drawings, forming part hereof, wherein a preferable embodiment of the invention is disclosed, for purposes of illustration.

Like reference-characters refer to corresponding parts in the several views of the drawings, of which—

Figure 1 is a plan view of the wrench; Fig. 2 is a longitudinal sectional view thereof; Fig. 3 is a bottom view of the wrench-head, with the housing partially broken away; Fig. 4 is a sectional view, on the line $z-z$, Fig. 2; Fig. 5 is a plan view of the outer jaw-engaging member; Fig. 6 is a side view of the inner jaw-engaging member; Fig. 7 is an end view thereof; Fig. 8 is a plan view of the jaws in their maximum position; Fig. 9 is a plan view of the jaws in their minimum position; Fig. 10 is an end view of a jaw; Fig. 11 is a view of an alternative form of jaw; Fig. 12 is a view of the inner nut; Fig. 13 is a perspective view of the pawl; Fig. 14 is a side view of the ratchet mechanism; and Fig. 15 is an end view of a portion of the ratchet mechanism.

Having more particular reference to the drawings, it will be seen that the handle 15 of the wrench comprises a bar 16, to each side of which is held, by screws 17 and ferrules 18, pieces 19 of wood or any other suitable material. Bar 16 at one end is formed with a relatively thick portion 20, 95 from which extends a widening flange portion 21, the end or edge 22 of which forms a circular segment.

A housing 23, having an aperture 24 and a flange portion 25, is held on the handle by 100 screws 26 which are seated in thick portion 20.

Seated in housing 23 is a member 27, preferably integrally formed, which comprises a ratchet-wheel 28, above the teeth of 105 which is formed a circumferential groove 29, in which edge 22 is adapted to seat and move, and the top of which forms a cup consisting of a bottom 30 and a side or flange 31. The bearing-surface 32 on the inner 110

side of this flange lies in an ellipse or substantially an elliptical continuous curve. Through member 27 is a centrally-disposed aperture 33, which is formed in the face of ratchet wheel 28 with a circular enlargement or seat 34 concentric with said ratchet-wheel, and in the bottom 30 of the cup with an enlargement or seat 35 which is of polygonal shape in cross-section.

Arranged to seat in outer member 27 is an inner member 36, which consists of a shank 37 formed to extend through aperture 33 and aperture 24. The shank is screw-threaded for a portion of its length from the end, it is formed with an enlarged portion 38 of the same shape in cross-section as and arranged to seat closely in seat 35, it has above portion 38 a continuation 39, and it is provided with a head 40, having a bearing-surface 41. In plan head 40 lies parallel with the bottom 30 and somewhat removed therefrom, and its edge or bearing-surface 41 lies in an ellipse or other continuous curve smaller than that of bearing-flange 31, but concentric and parallel therewith. This relative position is maintained by enlarged portion 38 seated in seat 35. Positioned in seat 34 is a nut 42 in engagement with the screw-threads of shank 37 and having therein wrench-engageable apertures 43, this nut operating to hold member 36 in place in member 27.

On shank 37, adjacent to nut 42, and seated in aperture 24 of housing 23, is a washer 44, and on the shank, outside of this washer, is a thumb-nut 45, which is arranged to clamp against the bottom of housing 23. It will be seen that handle 15 is pivoted at housing-aperture 24 on shank 37, and in addition held in place by engagement of edge 22 with groove 29.

The clutching elements or jaws 46 and 47 of the wrench are seated in cup 27 and between flange 31 and head 40. The jaws have interfitting extensions 48 and 49, which are arranged to lie between cup-bottom 30 and head 40, and the tongues 50 and 51 of which engage and are capable of movement on each side of shank portion 39. The complementary faces of the jaws are maintained in proper relative position by these interfitting extensions. The space between tongues 50 and 51 being centrally located, and shank portion 39 being at the center of the curves of the bearing-surfaces 32 and 41, it follows that the central longitudinal line between the jaws will always lie in an axis of the bearing-surface curves and that therefore the jaws will always be in an axial, and therefore in a most suitable, position to be operated upon by the bearing-surfaces.

Positioned in chamber 52 formed by flange portion 21 and housing 23 is a pin 53, on which is pivoted a double pawl 54, which

is arranged to coöperate with the teeth of ratchet-wheel 28.

The faces 55 of pawl 54 have therein notches or indents 56, which are engaged by leaf-springs 57. These springs are attached to pins 58 at or near the ends of a member 59 centrally pivoted on a pin 60 located in chamber 52. On member 59 is a lateral extension 61, to which is pivotally connected an arm 62, and this arm in turn is pivotally connected with a knob 63. The knob is arranged to be movable in a slot 64, and to be secured in one or the other limits of its movement by engagement with detents 65.

The jaws 46 and 47 of the wrench being engaged with a nut or other object to be turned, revoluble movement is given to the wrench-handle, and, pawl 54 coöoperating with ratchet-wheel 28, a rotative movement is thereby imparted to member 27 and the concentric head 40. The jaws remaining stationary with respect to the object, the cup and head simultaneously will be moved relatively to the jaws, so that the axial position of the jaws will be changed toward the minor axis of the curves of bearing-surfaces 32 and 41, and flange 31 bearing against the jaws causes them to have a tendency to approach each other and clamp the object. It will be seen that revoluble movement of the jaws in rotating the object is caused by their frictional engagement with flange 31, and that the greater the force exerted in rotating the flange the greater will be the force of the clamp of the jaws upon the object.

The clutch of the jaws upon the object is released by reversing the rotative movement of the cup and head, when the axial position of the jaws will be changed toward the major axis of the curves of the bearing-surfaces and their distance apart increased by operation thereon of the head, in an obvious manner.

Jaws 46 and 47 may be held in any fixed position desired by tightening thumb-nut 45, which operates to clamp the interfitting jaw-extensions 48 and 49 between head 40 and cup-bottom 30. The jaws may be removed for substitution by others by removing thumb-nut 45 and washer 44, when nut 42 is accessible for removal from shank 37, and member 36 then may be withdrawn and the jaws released. Other jaws may be set in place by reversal of this operation.

Pawl 54 is held in yielding engagement with ratchet-wheel 28 by means of leaf-springs 57.

It will be seen that when knob 63 is fixed in one of detents 65 one end of member 59 will be held by arm 62 nearer the pawl than the other, whereby pressure on the spring of that end is greater than on the other and the pawl is maintained against the ratchet-wheel on that side. The opera-

tion of the pawl may be reversed by moving the knob from one detent 65 to the other, in an obvious manner. The pawl may be held out of engagement on either side with the 5 ratchet-wheel by placing the knob in its medial position in slot 64, when member 59 will be in such position that the pressure of the springs on the pawl will be balanced and neither side of it forced against the 10 ratchet-wheel.

For the sake of convenience and brevity, the curves in which bearing-surfaces 32 and 41 are disposed have been described as elliptical or substantially elliptical, but it is 15 to be understood in construing the claims herein that applicant is not to be restricted to bearing-surfaces disposed in curves in all respects satisfying the geometrical definition of an ellipse, as his invention contemplates the disposition of the bearing-surfaces in 20 any curves of the approximate form of an ellipse or oval.

Having thus described my invention, what I claim as new, and desire to secure by Letters Patent, is—

1. In a wrench, the combination with the jaws, of outer and inner members having bearing-surfaces between which the jaws are disposed and arranged upon rotation in 30 either direction with respect to the jaws the outer member to force the jaws toward each other and upon reversal of rotative movement the inner member to force the jaws apart.

35 2. In combination with the jaws of a wrench, a rotatable member having a surface engaging one of said jaws and upon movement thereof with respect to said jaw operable thereon to force the jaw away from 40 an article clutched, said engaging surface lying in a substantially elliptical continuous curve.

3. In a wrench, the combination with the jaws, of an outer member having a curved 45 jaw-engaging surface, and an inner member having a curved jaw-engaging surface, the outer member being arranged when rotated in either direction with respect to the jaws to cause the same to clutch, and the 50 inner member being arranged upon reversal of rotation to positively release the clutch irrespective of the direction of initial rotation to clutch the jaws.

4. A wrench comprising a handle, an outer 55 member pivoted thereon and arranged to receive rotative motion therefrom, a flange on said outer member forming a continuous bearing-surface lying substantially in an elliptical curve, an inner member attached 60 to said outer member and having a bearing-surface complementary to that of the outer member, and jaws having portions disposed and capable of movement between said bearing-surfaces.

5. A wrench comprising a handle, an outer 65 member pivoted thereon and having a laterally polygonal recess, a flange on said outer member forming a continuous bearing-surface lying substantially in an elliptical curve, an inner member having a laterally polygonal portion seated in said recess and formed with a bearing-surface complementary to that of the outer member, and jaws having portions disposed and capable of movement 70 between said bearing-surfaces.

6. A wrench comprising a handle having an aperture therein, an outer member having an aperture therethrough polygonal in cross section for part of its length, an inner member having a screw-threaded shank extending through said apertures and a laterally polygonal portion seated in the polygonal portion of the outer member aperture, a binding-nut on said shank, and jaws having portions disposed and movable between 85 said outer and inner members.

7. A wrench comprising members having bearing-surfaces, jaws having portions movable between said bearing-surfaces, extensions on said jaws disposed between other 90 surfaces of said members, a shank on one of said members, and means on said shank whereby said extensions are clamped between said members.

8. In a wrench, the combination of an outer member having a bearing-surface, an inner member having a bearing-surface, jaws having portions movable between said bearing-surfaces, extensions on said jaws disposed between said members, and means whereby said extensions are bound between 95 said outer and inner members.

9. In a wrench, the combination of an outer cup-shaped member having a side bearing-surface, an inner member disposed therein and having a bearing-surface, jaws having portions movable between said bearing-surfaces, movably interfitting extensions on said jaws, and means whereby said extensions are bound between said outer and inner 105 members.

10. In a wrench, the combination of an outer cup-shaped member having a side bearing-surface, an inner member formed with a shank disposed in an aperture in said outer member and with a head having a bearing-surface, jaws having portions movable between said bearing-surfaces, movably interfitting extensions on said jaws disposed between the bottom of said cup-shaped member and said head, and means on said shank whereby said extensions are bound in fixed 110 position.

11. In combination with the jaw-carrying member of a wrench having ratchet-teeth, a handle pivotally secured to said member, a double pawl on said handle and coöperable with said ratchet-teeth, a pivoted arm, a 125

spring on said arm and engaging said pawl, and means whereby said arm is moved and said pawl held by said spring in yielding engagement with the ratchet-teeth, said 5 means comprising an extension on said arm, a knob, and pivotal connection between said extension and said knob, said knob coöperating with means for maintaining it in adjusted position.

10 12. In a wrench, a ratchet mechanism comprising, in coöperation with the ratchet-teeth thereof, the combination of a double pivoted pawl, an arm pivoted intermediate its ends, a leaf-spring attached to each end 15 of said arm and in engagement with said

pawl, and means for maintaining said arm and thereby said pawl in a predetermined position, said means comprising an extension on said arm, a grip member, and pivotal connection between said extension and 20 said grip member, said grip member coöperating with means for maintaining it in adjusted position.

In testimony whereof I affix my signature in presence of two witnesses.

CHARLES R. OLBERG.
